UNITED STATES PATENT OFFICE.

PHILEMON O. DICKINSON, OF NEWARK, NEW JERSEY.

DESIGN FOR A LID FOR BOXES.

SPECIFICATION forming part of Design No. 25,893, dated August 4, 1896.

Application filed June 12, 1896. Serial No. 595,363. Term of patent 34 years.

To all whom it may concern:

Be it known that I, PHILEMON O. DICKINSON, a citizen of the United States, residing at Newark, in the county of Essex and State 5 of New Jersey, have invented and produced a new and original Design for Lids for Boxes, of which the following is a description, reference being had to the drawing accompanying and forming a part of the same.

10 The present design relates generally to metal covers for boxes, bottles, or similar articles, particularly to such receptacles as powder-boxes, jewelry-boxes, &c.

15 The general outline of the cover herein shown and bearing the design is circular when viewed from above the illustration. The cross-sectional configuration is substantially that of an extended or flattened ellipsoid. In the center of the cover is the plain circular space

20 A. Surrounding this space is a roccoco band B. Beyond this band and covering the exposed curved or ellipsoidal part of the cover is a circular band bearing a design composed, essentially, of the raised centrally-located

rosette-flowers C, partially surrounded by the 25 conventionalized shell-and-leaf figures D, and between these combinations of rosettes and shell-and-leaf figures, reappearing at regular intervals, are located the flower figures E. This band of design is in cross-section, sub- 30 substantially of partial circular or ellipsoidal form. In other words, it rounds upwardly, as shown at C, and downwardly, as shown at F. Below such downward curvature F appears the cylindrical neck portion G of the cover, 35 designed to fit upon or over the box or other receptacle to which the cover is to be applied, and this neck portion is shown as having a plain surface.

The essential features of this design are 40 those features above expressed and described.

What is claimed as new is—

The design for lids of boxes and similar articles, substantially as shown and described.

PHILEMON O. DICKINSON.
